UNITED STATES PATENT OFFICE

GUSTAV LUDWIG HERTZ, OF HALLE-ON-THE-SAALE, GERMANY, ASSIGNOR TO N. V.
PHILIPS' GLOEILAMPENFABRIEKEN, OF EINDHOVEN, NETHERLANDS, A LIMITED
LIABILITY COMPANY OF THE NETHERLANDS

GAS FILLED DISCHARGE TUBE

Application filed December 13, 1926, Serial No. 154,550, and in the Netherlands December 16, 1925.

The invention relates to gas filled discharge devices and more particularly to devices comprising a solid incandescent electrode and a cold electrode.

5 The invention has for its object to provide a gas filled discharge tube which is adapted to rectify alternating currents and may be operated at very high voltages.

If an alternating current is supplied to a 10 gas filled discharge device provided with a cold electrode and a solid incandescent electrode, comprising an electron emitting material, the current will pass during the half cycle in which the cold electrode is positively charged owing to the fact that electrons emitted from the incandescent electrode move under the action of the electrostatic field between the electrodes in the direction of the cold electrode, causing thereby the 20 ionization of gas atoms.

During the inverse half cycle substantially no current passes if the voltage between the electrodes is relatively low. Consequently the 25 current conducted by the discharge tube is unidirectional, though the voltage applied to the electrodes is alternating. The discharge tube then acts as a rectifier.

By increasing the voltage a certain value 30 may be attained where ignition also occurs during the half cycle in which the incandescent electrode is positively charged. Operated at such a voltage the tube practically no longer serves as a rectifier.

Applicant has found that this critical value 35 of the operating voltage, above which a breakdown ensues in the direction from the solid incandescent electrode to the cold electrodes is materially increased if the cold electrode, which is intended to act as an anode, 40 is screened by a conductive body. The distance between the body and the screened electrode must preferably be in agreement with, or if possible, smaller than the distance 45 through which the first dark space extends during discharge.

In a construction of the discharge tube according to the invention an incandescent cathode for example an oxide cathode, may be used as the active cathode. The anode may 50 be cylindrical and bear by its outer surface

on the wall of the tube, the inner surface being screened by a cylinder which is axially arranged within the anode cylinder at a small intermediate space. It is not essential to give a determined potential to the covering body 55 but in some cases this may be advantageous.

The anode may be made of good heat conducting material, for example copper. The cathode is preferably arranged on one of the two sides of the coaxial cylinders approximately on their axes.

In order to ensure that the point of ignition to be attained in the direction from the screened electrode to the incandescent cathode, shall be as high as possible, the first 65 mentioned electrode is in the said construction provided with a very slanting edge on that side adjacent to the other electrode.

In order to provide for an equal distance at any point between the anode and the 70 screening element glass spacing sticks are provided having a diameter equal to the desired space between the two cylinders.

The invention may be more clearly understood by reference to the accompanying 75 drawing in which one embodiment is illustrated. In the drawing:

Fig. 1 shows in elevation an incandescent cathode discharge tube according to the invention.

Fig. 2 is a section taken on the line II-II Fig. 1.

Fig. 3 is a vertical partial section of the screened electrode by a plane passing through the axis of this electrode.

Referring to Fig. 1 numeral 1 designates a gas filled discharge tube, 3 is a cylindrical conductive body, by which the cylindrical anode 2 is screened; 4 is an incandescent cathode, 5 and 6 are leading-in wires to the cathode and 7 is one of the glass spacing sticks separating the two cylinders.

What I claim is:

1. A gas filled electron discharge rectifier, 90 comprising a solid incandescent cathode, an anode and an imperforate conductive body, said body screening the anode for the purpose of preventing a discharge in the wrong direction.

2. A gas filled electron discharge rectifier, 100

comprising a solid incandescible cathode, an anode and an imperforate conductive body at a distance from the anode substantially that of the distance through which the first dark space extends during discharge for the purpose of preventing a discharge in the wrong direction.

3. A gas filled electron discharge rectifier comprising the combination of a solid incandescible cathode, an annular shaped anode and a coaxial cylindrically shaped conductive body within said anode and spaced therefrom an insulating distance, screening the anode for preventing the discharge in the wrong direction.
- 10 4. A gas filled electron discharge rectifier comprising the combination of a solid incandescible cathode, an annular shaped anode having a sharp slanting edge at the end toward the cathode, and a coaxial cylindrically shaped conductive body within said anode and spaced therefrom an insulating distance, screening the anode for preventing the discharge in the wrong direction.
- 20 5. In testimony whereof I affix my signature at the city of Leipzig, this 23d day of November, 1926.

GUSTAV LUDWIG HERTZ.
